UNITED STATES PATENT OFFICE.

ELMYR A. LAUGHLIN, OF OREGON, ILLINOIS.

COUPLER CENTERING DEVICE.

Application filed September 16, 1924. Serial No. 738,032.

This invention relates to new and useful improvements in railway draft appliances, and particularly to centering devices for coupling heads.

5 One object of the invention is to provide a device of this character which is simple in construction, and which is durable and effective in operation.

Another object is to provide a carry iron 10 and rockers of such construction that wear is reduced to a minimum, and the proper play of the coupler stem permitted with the use of the minimum amount of material.

Another object is to provide a device of 15 this character wherein means are provided for properly lubricating the carry iron and coupler stem.

A further object is to provide rockers for supporting the carry iron whereby the minimum amount of friction is produced between 20 the rockers and iron, thus preventing undue wear, and lengthening the life of the parts.

Other objects and advantages will be apparent from the following description when 25 taken in connection with the accompanying drawing.

In the drawing:

Figure 1 is a front elevation of the centering device, the coupler stem being shown in 30 section.

Figure 2 is a side elevation of said device.

Figure 3 is a vertical longitudinal central section view on the line 3—3 of Figure 1.

Figure 4 is a vertical transverse sectional 35 view on the line 4—4 of Figure 3.

Referring particularly to the accompanying drawing, 10 represents the end sill of a car, to which is secured the casting, represented as a whole by the numeral 11. This casting comprises a rectangular body 12, having a horizontal rearwardly extending flange 13, on its upper portion, which is properly riveted to the sill. Through the vertical portion of the casting there is 40 formed a rectangular opening 14 through which the coupler stem 15 is disposed. Formed transversely on the plate or casting, beneath, and rearwardly of the opening 14, is a recess or pocket 16, which has the openings 17 in its bottom wall. Disposed within this pocket are the rockers 18, which stand vertically and have upper carrying cam faces 19 and lower supporting cam faces 20, respectively, the latter of which bear on the 45 said bottom wall of the pocket. Formed integrally on the faces of the cams are the

lugs 21 and 22, respectively, the latter of which extend into the openings 17. Resting on the upper ends of the rockers 18 is the carry iron 23, said iron being in the form 60 of a channel which receives the before-mentioned coupler stem 15 between its vertical end walls 24. Depending from the front and rear edges of the carry iron are the flanges 25 and 26, which embrace therebetween the upper portions of the rockers 18, and in the horizontal portion of the carry iron are openings 27 which receive the lugs of the upper ends of the rockers. It will be noted, upon reference to Figure 4, of the 70 drawings, that the openings 27 extend entirely through the bottom wall of the pocket of the striking-plate. By this construction dust, dirt, cinders, and the like are permitted free escape from the pocket, whereby to prevent accumulations thereof between the rockers and the said bottom wall of the pocket. Such accumulations would, in time, tend to become packed by the rockers, and thereby lift the rockers, with the result that 75 the entire mechanism would be thrown out of gear, and the pocket wall and rockers worn out of shape. Formed through the vertical portion of the casting 11, and above the said pocket 16, is the before-mentioned 80 opening 14, and disposed against the rear face of this portion of the casting, and with its end in covering relation to said opening, is the member 28, said member being secured to the casing by the plates 29. 90

Formed through the side walls of the casting 11 are the openings 11', which permit the easy insertion and removal of the rockers and carry iron, in the assembling and disassembling of the device. 95

Disposed on the carry iron and having the coupler stem resting thereon, is a hard steel wear plate 31, the ends of which are cut out at 31' to straddle the end flanges 24 of the carry iron. The corners of the plate 31 are 100 cut out to permit passage by the striking plate. The said plate is formed with openings 30 to receive and retain lubricant for the coupler stem.

It will be noted that the arcs of the ends 105 of rockers are of greater diameter toward the ends than at the centers, and that the centers are formed with flat spots 32. Thus, when the carry iron moves to one side, with the coupler stem, the tendency of the rockers 110 is to lift the carry iron, and the coupler stem, as soon as the side force is removed,

the weight of the carry iron, and the coupler stem press down on the ends of the arcs of the rockers and cause them to rock into vertical position, with the result that the iron will rest on the flat spots of the rockers, and maintain the parts from continuous rocking.

The upper edge of the front wall of the pocket 16 is turned horizontally inward, as shown at 33, and the lower end of the front depending flange or wall 25 is extended horizontally forward to lie beneath the flange 33, whereby to prevent upward movement of the carry iron under the influence of jars or shocks of the car, and whereby to maintain a constant and uniform contact between the carry iron and the rockers. Attention is particularly called to the fact that the rockers have a true rolling action with respect to the carry-iron and striking-plate, thus greatly reducing wear of the parts.

What is claimed is:

1. In a railway draft appliance, a striking-plate having openings, a carry-iron having openings, a rocker mounted between the striking-plate and carry-iron and having a carrying face and a supporting face, said faces being arcuate, and lugs projecting from each of said arcuate faces and into said openings.

2. The combination with a coupler including an apertured striking-plate and an apertured carry-iron, of rockers mounted between the striking-plate and carry-iron and having arcuate supporting and carrying faces, the former being eccentric to the latter and having projections extending into the apertures of the striking-plate, the latter having projections extending into the apertures of the carry-iron.

3. In a railway draft appliance the combination with a carry-iron having guides thereon and a coupler stem supported thereon and between the guides, of a plate between the coupler stem and carry-iron provided with terminal bifurcations straddling the coupler stem guides for maintaining said plate in position.

4. In a railway draft appliance the combination with a carry-iron having guides thereon and a coupler stem supported thereon and between the guides, of a plate between the coupler stem and carry-iron provided with terminal bifurcations straddling the coupler stem guides for maintaining said plate in

position, said plate having lubricant receiving openings.

5. A railway draft appliance having in combination a striking plate having a coupler receiving opening and a pocket below said opening, a coupler supporting carry iron fitted within the pocket, rocker members interposed between the carry iron and the striking plate within the pocket, a wear plate interposed between the carry iron and the coupler, interengaging means between the rocker members and the carry iron and between the rocker members and the striking plate, said striking plate being formed with side openings for inserting and removing the parts and cooperating means between the carry iron and a wall of said pocket for limiting the rising movement of the carry iron.

6. A railway draft appliance comprising in combination a striking plate having a coupler stem opening therein and a transversely extending pocket below the opening, rockers supported within the pocket, a carry iron supported upon the rockers, a wear plate interposed between the rockers and the coupler stem, interengaging means between the rockers and the carry iron and between the rockers and the striking plate for maintaining the parts in proper relation in their transverse movement, and a retaining flange on the striking plate positioned to overlie a portion of the carry iron to maintain the latter from vertical displacement.

7. A railway draft appliance comprising in combination a striking plate having a coupler stem opening therein and a transversely extending pocket below said opening, rockers supported within the pocket, a carry iron supported on the rockers, a wear plate interposed between the rockers and the coupler stem, interengaging means between the rockers and the striking plate and between the rockers and the carry iron for maintaining the parts in proper relation in their transverse movement, and a retaining flange on the striking plate positioned to overlie a portion of the carry iron to retain the latter from vertical displacement and said carry iron being formed with depending flanges positioned to embrace the rockers to retain the latter in their vertical position.

In testimony whereof, I affix my signature.

ELMYR A. LAUGHLIN.
